(57) **CLAIM**

The ornamental design for a bracket for inversion apparatus, as shown and described herein.

DESCRIPTION

FIG. 1 is a front perspective view of a bracket for inversion apparatus showing our new design;

FIG. 2 is a top view thereof;

FIG. 3 is a bottom view thereof;

FIG. 4 is a front view thereof;

FIG. 5 is a rear view thereof;

FIG. 6 is a first side view thereof;

FIG. 7 is a second side view thereof; and,

FIG. 8 is a rear perspective view thereof, shown in an environment of use.

The broken lines shown in FIG. 1-8 illustrate portions of the bracket for inversion apparatus that form no part of the claimed design.

The additional broken lines shown in FIG. 8 are for purposes of illustrating environment only and form no part thereof.

1 Claim, 8 Drawing Sheets
